HINGE CONNECTION

Filed June 25, 1927

UNITED STATES PATENT OFFICE

HERMAN M. GASSTROM, OF MOUNT VERNON, NEW YORK

HINGE CONNECTION

Application filed June 25, 1927. Serial No. 201,375.

The present invention has reference to articulated joints and pertains more especially to hinges for connecting the arms of two-foot measuring rules.

5 Primarily the invention has for its object to produce an improved hinge of the type specified, adapted for manufacture, assembling and attachment to the ends of the sections comprising the rule, by automatic machinery, thereby avoiding all manual operations and reducing the cost of manufacture to a minimum.

A secondary object is so to construct a hinge for the purpose set forth, that the portions thereof which are affixable to the arm sections of the rule, can be secured to the same by clinching without the use of rivets or like extra parts.

Thirdly, the invention contemplates making a hinge of the nature referred to, wherein the pivots connecting the coacting parts are held from endwise movement and so proportioned as not to require finishing after being assembled.

25 Fourthly, the invention aims to provide a hinge of the kind mentioned, admitting of the opposed and conjoined extremities of the rule arms being recessed alike by means of one forming tool following a single thru path, thus eliminating sharp corners and shoulders necessitating several settings and cutting operations.

A fifth object is to supply a hinge of the character described, composed of a minimum 35 number of simple parts combined to make up a light but amply strong and rigid structure, not likely to become disarranged; besides capable of being produced by the least expensive labor.

40 Other objects and advantages of the invention will be obvious and more fully brought out in the detailed description hereinafter contained.

Generally stated, the invention consists of 45 the novel improvements, parts, combinations, and features of construction herein shown and described, and particularly pointed out in the appended claims.

50 A practical embodiment of the invention is illustrated in the drawings hereto annexed,

which form an integral part of this specification, and wherein similar characters of reference are employed to designate corresponding elements wherever they occur in the several views.

55 Referring to the said drawings which depict this improved rule hinge on a considerably enlarged scale:

Figure I is a fragmentary, perspective view of a portion of a pocket rule, showing the middle or laterally folding joint;

Figure II is a perspective view of one of the hinge elements shown by the preceding figure;

Figure III is a view similar to Figure II, 65 illustrating the same element reversed or turned over end for end so as to constitute the companion member of the sidewise swinging hinge;

Figure IV is also a perspective view, representing a spacer interposed between the coacting parts of the aforementioned hinge members;

Figure V is a like view to the foregoing, 75 picturing a hollow rivet used to connect the hinge members and the spacer together;

Figure VI is a view similar to Figure I of a modified form of the invention;

Figure VII is a sectional elevation of one 80 of the hinge elements shown in Figure VI, the section being taken on the line VII—VII of said figure, looking upwardly thereon;

Figure VIII is a view similar to Figure VII, of the other one of the last-named hinge elements, the section being had on the line 85 VIII—VIII of Figure VI.

Figure IX is a side elevation of a pin employed in connecting together the hinge members shown by Figures VII and VIII.

Figure X shows a side elevation of a modified spacer.

Succinctly outlined, the invention forming the subject matter hereof, comprises correspondingly shaped hinge elements having oppositely disposed ears and recesses conforming therewith, arranged in reversed relation one to the other. These elements are struck up of sheet metal and have integrally formed cheeks and backing members adapted to take over and clasp therebetween the faces and

55

100

sides of the rule sections near the adjacent ends thereof. The inner or free perimetral edges of the cheeks are provided with counter-clockwise extending flanges receivable within 5 grooves cut therefor in the opposed surfaces of the rule sections. Prongs projecting from and in the plane of the above mentioned flanges, serve when forced into the material of which the rule sections are composed, to 10 anchor the hinge elements thereto. Interposed between the beforenamed ears and reaching under a portion of the cheeks, is a spacer or filling washer. A hollow eyelet passed centrally thru the latter and clinched 15 over the ears, maintains the parts last referred to, in cooperative alignment.

While the accompanying drawings illustrate the preferred and what is now considered to be the best form of the invention, it 20 will be observed that the same is shown and described herein by way of example only, and that other serviceable embodiments of this improved hinge are within the range of practical achievement, whether containing the 25 totality or a less number of the novel features of construction herein disclosed.

Before commencing the detailed description of the invention, it will be stated, in order to convey a clearer idea of the scope thereof, 30 that such parts of the improved device as are indicated by letters of the alphabet throughout the present specification and accompanying drawings, appertain strictly speaking, to a known species of two-foot measuring rule. 35 On the other hand, those parts of the device, which are designated by numerals, may be considered as entirely belonging to the invention. It is understood that no claim is made to any of the known parts aforesaid as 40 possessed of actual originality, save that thru their association with the various elements of the improved hinge joint, they form a number of combinations serving to accomplish several new and useful purposes.

45 Having now particular reference to Figure I of the annexed drawings, the letter "A" denotes one of the middle or leg sections of a rule; B, the other or companion leg section. These sections are respectively provided at 50 one or more of their edges with graduations, d, e, f, which register and correspond with certain measurements, such as inches and fractions thereof, as is customary in four section, two-foot, folding pocket rules.

55 The peculiar construction and arrangement of the head and knuckle joints which connect the rule's middle sections or arms, and the latter with the end sections or legs, will now be described with particularity. Referring 60 first to the head or central hinge joint, it will be perceived that the same comprises cheek members 11, 13, and backing pieces 15 bent from one edge of the former in right-angular relation thereto. These members and the 65 backing are conveniently pressed from metal,

preferably sheet brass, and have integrally formed therewith, circularly shaped ears 17 and similarly rounded recesses 19, which are coextensive and disposed in the same parallel planes as the cheeks 11, 13, respectively. The 70 aforementioned members with their backing and the ear, which conjointly constitute a hinge element, are applied in pairs, in inverted relation, to the adjoining extremities of the middle sections A and B. The ears 17 75 of the paired elements are oppositely disposed with respect to the recessed portions 19, fitting into the latter so as to receive support therefrom.

As will be noticed from Fig. I, the cheek members are made to take over the opposed wider sides A1, B1, of the rule sections, near the terminals a and b thereof. The outer limits or side edges 21, 23, of the members 11, 13, are located in a plane passing radially thru the centre of the ears 17. Furthermore, said edges 21, 23 are disposed in right angular relation to the narrower sides of the sections A, B, one whereof is denoted A2, coinciding as well with the said terminals a, b, 90 of these sections. The backings 15 which are included between each pair of the said cheeks 11 and 13, are also in opposition to the before named narrow sides of the rule sections, and these together with the wider sides of the latter are dressed off or routed to a depth corresponding to the thickness of the metal of which the hinge elements are made, so that when the same are placed in their assigned positions, they will lie flush with all three 100 faces of the rule sections encompassed by the elements in question.

From the free, inner margins 25, 27, of the cheeks or wings 11, 13, which are arcuately curved, extend in counterwise directions, inwardly of the gap formed intermediately of the before named members, lips or flanges 29, 31, following the contours of said margins 25, 27 respectively. These lips are designed to enter grooves 33, 35 (Fig. I) cut into the opposed wider faces A1, B1, of the middle sections of the rule. By reason of the fact that the before named grooves follow a like circular arc to the margins 25, 27, these 115 grooves can be milled with a tool carried by the same spindle or arbor whereon are mounted the cutters employed in routing the faces A1, B1, incidental to accommodate the seating of the cheeks 11, 13 thereon. From the foregoing it will be understood that the cheek seating surfaces as well as the lip receiving grooves, on both sides of the sections A, B, 120 may be simultaneously incorporated therein, thus effecting a considerable saving of time and expenses. The cheeks in question can be readily applied to the seating portions referred to, because the former will yield to a certain extent without becoming distorted, sufficiently nevertheless, to enable the said cheek members to open up, permitting the 125

10 lips 29, 31 to pass over the seats alluded to, until these lips are pushed in far enough to reach the grooves 33, 35, into which the said lips or flanges 29, 31, will immediately snap or find lodgement. In order to positively anchor the hinge elements in their assigned positions to the rule ends and preventing displacement thereof, the cheeks of the said elements are furnished with prongs or teeth 37, 39, adapted to be driven or forced into the wood whereof the sections of the rule are generally composed. As illustrated, these prongs may form continuations of and extend in the same plane and direction as 15 those of the lips 29, 31, namely, counterwise one to the other.

20 Interposed between the ears 17 of the cheek members 11, when the hinge elements are assembled in converted and inverted relation, is a spacer or filler 41, which may be in the nature of a comparatively thick disc or washer of appropriate material, preferably metal.

25 While the spacer in question is represented as being made of one piece of stock, it is obvious that the same can be composed of two or more such washers superimposed upon one another. In Fig. 10 the spacer is indicated to comprise the central washer 70 and the 30 similar end washers 71. The latter have each the recessed portion 72. An axial opening 73 extends through the washers of the spacer. The pindle 51 functions with this modified spacer as described for the spacer 41. It will be observed with reference to Fig. I, that said 35 spacer 41 is of a size larger than either one of the ears 17, or the inside contours of the recessed portions 19. The borders or edges of both of these parts which overlie the said 40 spacer, are supported thereon and afford protection against injury or disarrangement. The inside corners of the rule sections in order to accommodate the spacing washer 41, are gouged out as indicated at 43, Fig. I. 45 Similarly, the adjacent portions of the backings 15, are provided with notches 45, (Figs. I and III) affording the proper clearance for the hereinbefore mentioned spacer. Centrally the ears 17 and the spacer 41 are pierced 50 by openings 47, 49, respectively, capable of having passed therethru the shank of a pindle 51 that constitutes the connecting medium between the paired hinge elements. For the purpose of enabling the heads or upset extremities 53 of this pindle, which incidentally may consist of an eyelet or hollow rivet, to lie flush with the exterior faces of the ears 17, the latter are preferably countersunk or pressed inwardly around the openings 47 to 55 simulate the recessed seats denoted at 55 (Figs. II and III). The spacer 41 is treated in a like manner on both of its flat faces to afford a clearance for each of the aforementioned ear seats 55. It is an easy matter, 60 when the hinge parts proper become worn

and loose, to press together the flanged over end portions 53 of the connecting pindle 51, in order to take up wear therebetween. Moreover, it will be comprehended, that if a snug working fit is had interadjacent the 70 contacting surfaces of the spacer 41 and its recesses 49, the frictional resistance of these surfaces upon one another, will materially aid in maintaining the hinge elements and the thereby carried rule sections firmly in 75 adjusted position.

The arrangement of the knuckle joint which hingedly couples the outer extremity of the arm A together with the adjacent end of the leg C, corresponds approximately 80 with the articulated connection previously referred to. A modification and construction embodying the same invention and analogous principle is disclosed in Figs. VI to IX. In these several views all parts substantially equivalent to those already described, are designated by the same reference characters to which letter exponents have been suffixed.

85 Referring to the figures first named, the structure therein shown, comprises also cheeks and backings 11x, 13x, and 15x, 15y. In this instance, the latter coact with the wider under sides A1, C1, of the rule sections A and C, while the aforementioned cheeks engage the narrower sides A2, C2, of the said sections. It will be perceived that both 90 of the cheeks 11x included in the outermost or left hand one of these hinge elements, are located opposite one another, near the end of the leg section C, and also that paired ears 17x have their aligned axes in the plane of the backing 15x, being formed preferably integral therewith, in proximity to the outside faces of the said cheeks and extending counterwise inwardly therebetween. The other hinge element consists of the oppositely facing wing members 13x and the backing 15y, of which the latter takes over 95 the corresponding side of the outer extremity of the arm A, and is provided centrally thereof with a single but wider ear 17y, adapted to fit in between the ears 17x of the companion element first referred to. The last mentioned backing 15y as well as the 100 cheeks or wings 13x are cut out as shown at 19x, to afford the proper working clearance for the above named paired ears 17x. By virtue of the construction hereinbefore described, the ear 17y serves as a filler or 105 spacer intermediate the narrower, similar appendages 17x, thus dispensing with a separate adjunct for this purpose. Both the narrower ears 15x and the wider one 15y, are 110 provided with tongues 59, 61 respectively, constituting extensions or continuations thereof. It will be noticed that the aforementioned tongues are bent or folded upon the backings 15x and 15y, from which their said 115 ears are formed. The ends of the leg and 120

arm sections of the rule which overlie these tongues, serve to keep the latter in place or from opening up under stress being applied thereto.

In conformity with the other species of hinge, the curved outer edges of the cheeks 11 α , 13 α , are provided with inwardly projecting lips 29 α , 31 α , having similar prongs 37 α , 39 α , respectively, as those of the first mentioned type of articulated connection. A pintle 51 α which operatively couples the single and double ears 17 γ and 17 α , to one another, are preferably lodged within both of these ears before the same and the therewith connected tongues 61 and 59 are closed or pressed together. Means serving the same purpose as the upset ends of the first mentioned pintle, namely to prevent axial displacement thereof, relatively to the ears 17 α , 17 γ , may advantageously consist of a lug 53 α (Figs. VIII and IX). This lug 53 α , when the pintle 51 α is placed in its assigned position, lies wholly within the central ear 17 γ , and at such time as the same and its tongue 61 is squeezed down, the material whereof these last named parts are composed, envelops the lug in question and holds the latter from moving endwise in either direction. A protuberance 63 is thus formed with the ear 17 γ which encompasses the lug 53, seen most clearly in Figs. VI and VIII.

The routing of the faces and sides of the adjoining extremities of the arms and legs of the rule sections to provide seats for the cheeks and backings of the knuckle jointed hinge elements, as well as the grooves to receive the cheek lips, is performed in the same manner as for the sidewise swinging central hinge connection.

It is entirely feasible and practical to do all the work required on the rule sections by automatic machinery and as will be manifest the two forms of hinge elements herein disclosed can be produced and assembled by gang dies operating in sequence and automatically. Even to place and affix the completed hinge elements onto the prepared ends of the rule sections, may be effected by special devices without any manual labor or handling. Not alone is the cost of production of a measuring rule made as herein described, very low, still such a rule will be both strong and rigid, there being besides no likelihood of the same getting out of order.

In its broader aspects, the invention is not limited to the precise features of construction and arrangement of parts herein shown and described, nor to any particular means by which it can be carried into effect, as many changes may be made in the details without departing from the principles of the invention or sacrificing its chief advantages.

What I desire to secure by Letters Patent of the United States, and claim is:—

1. An articulated joint of the type speci-

fied comprising in combination with the sections of a measuring rule having the adjacent extremities thereof oppositely grooved and provided with like seating portions, a pair of elements including flanged cheek members 70 adapted to take over said portions with the flanges thereof lodged in said grooves, said flanges being furnished with prongs capable of entering the sections beneath the grooves therein, and hingedly connected ears coextensive with said members disposed in staggered relation therefrom, said ears serving to operatively unite the elements and the rule sections carried thereby.

2. An articulated joint of the type specified, comprising in combination with hingedly connected rule members of rectangular cross section having their adjacent ends in abutting relation when the rule is extended, a pair of joint parts composed of sheet metal 80 and each embodying cheeks designed to take over opposite parallel faces of a rule member, said cheeks being integrally connected by a backing portion adapted to overlie an intermediate edge of the rule member, the 85 said cheeks being provided at their edges with inturned shallow flanges capable of engaging supplemental grooves in the corresponding faces of the rule members, said joint parts including complementary hinge 90 elements, and means pivotally connecting the latter.

3. An articulated joint of the type specified, comprising in combination with hingedly connected rule members of rectangular 100 cross section having their adjacent ends in abutting relation when the rule is extended, a pair of joint parts composed of sheet metal and each embodying cheeks designed to take over opposite parallel faces of a rule member, said cheeks being integrally connected by a backing portion adapted to overlie an intermediate edge of the rule member, the 105 said cheeks being provided at their edges with inturned shallow flanges capable of engaging supplemental grooves in the corresponding faces of the rule members, said joint parts being formed with centrally apertured hinge ears disposed in opposed complementary relation, and pivotal means connecting said ears.

4. An articulated joint of the type specified, comprising in combination with hingedly connected rule members of rectangular cross section having their adjacent ends in abutting relation when the rule is extended, a pair of joint parts composed of sheet metal and each embodying cheeks designed to take over opposite parallel faces of a rule member, said 120 cheeks being integrally connected by a backing portion adapted to overlie an intermediate edge of the rule member, the said cheeks being provided at their edges with inturned shallow flanges capable of engaging supplemental grooves in the corresponding faces of 125

the rule members, said joint parts being formed with centrally perforated hinge ears disposed in opposed complementary relation, a similarly apertured spacing disc located 5 between said ears and substantially equal in thickness to the rule members, and a tubular pindle passing through the aligned openings in the hinge ears and said spacer, said pindle including end flanges compressible to retain 10 the joint parts in pivotal connection.

5. An articulated joint of the type specified, comprising in combination with hingedly connected rule members of rectangular cross section having their adjacent ends in abutting 15 relation when the rule is extended, a pair of joint parts composed of sheet metal and each embodying cheeks designed to take over opposite parallel faces of a rule member, said cheeks being integrally connected by a backing 20 portion adapted to overlie an intermediate edge of the rule member, the said cheeks being provided at their edges with inturned shallow flanges capable of engaging supplemental grooves in the corresponding faces of 25 the rule members, said joint parts being formed with centrally perforated hinge ears disposed in opposed complementary relation, a similarly apertured spacing disc located between 30 said ears and substantially equal in thickness to the rule members, the faces of said spacer adjacent its aperture being countersunk and the margins of the perforations in the hinge ears being depressed to enter the latter, and a pindle passing through the 35 aligned openings in the spacer and the said ears, said pindle including ends compressible to retain the joint parts pivotally connected.

6. An articulated joint of the type specified, comprising in combination with hingedly connected rule members of rectangular cross section having their adjacent ends in abutting relation when the rule is extended, a pair of joint parts composed of sheet metal and each embodying cheeks designed to take over opposite parallel faces of a rule member, said cheeks being integrally connected by a backing 40 portion adapted to overlie an intermediate edge of the rule member, the said cheeks being provided at their edges with inturned shallow flanges capable of engaging supplemental grooves in the corresponding faces of the rule members, said joint parts being formed with centrally apertured hinge ears 45 disposed in opposed complementary relation, and pivotal means connecting said ears, the cheek of one joint part being cut away arcuately to fit the periphery of the hinge ear on the other one of said parts.

7. A joint part for articulated joints of the type specified, said joint part being composed of sheet metal and comprising substantially parallel cheeks designed to take over opposite faces of a rule member, said cheeks each having an arcuate edge and being 50 connected at an edge opposite said arcu-

ate edges by an integral backing portion adapted to overlie another face of the member, the arcuate cheek edges opposite said backing portion being provided with opposed inturned lips conforming to the curvature of the free arcuate edges thereof, said lips being adapted to engage complementary grooves in the first named faces of the rule member, and the said joint part having an extending element capable of being united 70 for pivotal movement with a similar element on a companion joint member.

8. A joint part for articulated joints of the type specified, said joint part being composed of sheet metal and comprising substantially parallel, cheeks designed to take over opposite faces of a rule member, said cheeks each having an arcuate edge and being connected at an edge opposite said arcuate edges by an integral backing portion 80 adapted to overlie another face of the member, the arcuate cheek edges opposite said backing portion being provided with opposed inturned lips conforming to the curvature of the free arcuate edges thereof, said lips being adapted to engage complementary grooves in the first named faces of the rule member, and the inner edges of the lips on the 85 said cheeks having prongs pointing one towards the other and capable of entering into the member beneath the bottoms of said grooves, and the said joint part having an extending ear element for hingedly uniting the same to a similar element on a companion joint member.

9. A joint of the character described for the middle sections of a measuring rule, comprising for each section of the rule a pair of parallel cheek members, a backing at right angles to and connecting each pair of parallel cheek members, each pair of cheek members with its backing adapted to be seated on one of the adjacent sections of the measuring rule, the inner corners of the side and end faces of the sections of the rule adjacent to said backing being gouged out, and the inner end of each backing having a notch formed therein, adjacent to the gouging in the rule sections, an ear having an axial perforation formed with one of the cheeks of each pair of cheeks, the said ears being oppositely positioned relatively to each other, axially apertured spacing means interposed between said ears, the gouged out portions of the middle sections of the rule and the notches in the backings forming clearance spaces for said spacing means, and pivotal means uniting said ears passing through their perforations and through the aperture 100 of said spacing means.

HERMAN M. GASSTROM.
